UNITED STATES PATENT OFFICE.

STEPHEN STOUT, OF AXTELL, KANSAS, ASSIGNOR OF ONE-HALF TO HOMER K. HARNESS, OF AXTELL, KANSAS.

WATER SCREEN AND FILTER.

SPECIFICATION forming part of Letters Patent No. 748,230, dated December 29, 1903.

Application filed July 31, 1903. Serial No. 167,778. (No model.)

To all whom it may concern:

Be it known that I, STEPHEN STOUT, a citizen of the United States, residing at Axtell, in the county of Marshall and State of Kansas, have invented a new and useful Water Screen 5 and Filter, of which the following is a specification.

This invention relates to water-filters, and particularly to the type designated as "servo-ice-pipe" filters.

The principal object of the invention is to provide means for efficiently cleaning the filter and for generally improving the construction thereof.

Other objects and advantages of this invention will be specifically described hereinafter and the novel details of construction of the preferred embodiment of the device will be specifically described in the following description, reference being had to the accompanying drawings, in which—

Figure 1 is a vertical longitudinal sectional view of a filter constructed in accordance with my invention. Fig. 2 is a detail perspective view of the collector and screen, and Fig. 3 is a cross-sectional view through the screen and the supporting means.

1 designates the outer shell or casing, illustrated as being substantially cylindrical and supported upon suitable standards 2. The bottom 3 of the casing is substantially conical to direct the liquid toward the vertex thereof and into the discharge-pipe 4. The filtering-bed 5 consists of suitable granular material, which is packed within the receptacle 1 and is supported above the opening in the bottom of the receptacle by a grate 6, so that the water will not direct it into the discharge-pipe 4. A screen 7 is fitted within the receptacle and rests above the filtering-bed, so as to confine the material between it and the grate, whereby accidental displacement thereof will be prevented.

Positioned above the filtering-bed is a separator 8, which is provided with a collecting-pan 9, coinciding in form with the shape of the casing 1.

The collecting-pan 9 is provided with a circumferential flange 10, having an annular groove 11, within which is a packing 12. The 50 groove 11, within which is a packing 12. The edge of the flange may be notched, as at 13,

to receive one end of the packing-strip, which will then be wound around the flange and rest within the groove 11. The pan rests upon and is supported by an intermediate 55 circumferential inwardly-disposed bead 14, formed in the receptacle, so that when the pan is forced down within the receptacle the bead will constitute a seat therefor.

The screen is preferably pyramidal in form 60 and is shown as surrounding a central opening 15 in the bottom of the collecting-pan 9. The corners of the screen are braced by the converging bars 16, which connect at the apex of the screen and enable said screen to 65 withstand any pressure due to the introduction of the water into the receptacle through inlet-pipe 17, carried by the removable cover 18. The braces 16 also serve as intermediate connections between the ring 19 and the pan, 70 so that a sufficient pull upon the ring will effect the removal of the pan. It will be observed that the pan and screen are constructed together, so that one acts as a brace for the other, and thereby providing considerable 75 strength to the entire structure.

In actual practice the panels 20 of the screen 8 will be attached to the braces 16 by inserting the edges of the panels in grooves in the braces, after which the edges of the 80 braces are crimped over the edges of the panels to secure them.

All of the parts being assembled, water is admitted into the filter through the inlet-pipe 17, so that it will strike the apex of the screen 85 and be separated or deflected to pass through the panels and through the filtering-bed into the discharge-pipe 4. The coarser particles of extraneous matter will pass over the screen and be deposited into the collecting-pan, 90 while the finer particles will be carried by the water through the mesh of the screen and separated by the filtering-bed before the water finally passes out through the discharge-pipe 4. 95

When desired, the top of the receptacle can be removed and the screen and collecting-pan may readily be detached, so as to relieve the filter of the collected impurities, and, if desired, the filtering-bed can also be cleansed 100 by taking out the screen 6.

Inasmuch as the screen-panels are disposed

at substantially a vertical plane it will be impossible for the meshes to become clogged by leaves, &c., so that a free passage of the water through the screen will at all times be assured.

It will be seen that the device is efficient, durable, and easy to assemble.

I claim—

1. In a filter, a casing, a separator fitting in the casing and comprising a pan having a central opening an upstanding flange peripherally disposed and a part of the pan and having a groove, with a notch in the flange, a packing engaging the notch and seated in the groove and a screen covering the opening and having upstanding converging panels.
2. In a filter, a casing, a separator fitting in the casing and comprising a collecting pan, having a groove provided with a notch in the edge of the pan, a packing in the groove one end of which engages the notch, and a screen carried by the pan.
3. In a filter, a casing, a separator fitting in the casing and having a peripheral flange with a circumferential groove and a notch in

the flange, and a packing in the groove, one end of which engages the notch.

4. In a filter, a casing containing a filtering-bed, and a collecting-pan above the bed having a groove and a packing in the groove 30 frictionally engaging the casing.

5. In a filter, a casing having an inverted conical bottom, a discharge - pipe leading therefrom, an intermediate inwardly - disposed bead carried by the casing, a grate 35 above the opening, a granular filter-bed on the grate, a screen above the granular material and resting upon the bead, a collecting-pan on the screen and engaging the sides of the casing, said pan having an opening, a 40 screen covering the opening, and a cover for the casing having an inlet-opening.

In testimony that I claim the foregoing as my own I have hereto affixed my signature in the presence of two witnesses.

STEPHEN STOUT.
